FLUID MIXING AND SERVING MECHANISM

Clarence Johnson, Orfordville, Wis., assignor, by
mesne assignments, to Rockwell Manufacturing
Company, Pittsburgh, Pa., a corporation of
Pennsylvania

Application October 30, 1948, Serial No. 57,489

8 Claims. (Cl. 99—275)

1

This invention relates to mechanisms for mixing and serving fluids automatically in predetermined quantities, and more particularly to mechanisms for serving liquids and a gaseous fluid mixed in predetermined quantities to form a drink.

Many of the ordinary bottled drinks found on the market today consist of nothing more than a syrup mixed with water that has been charged by a gaseous fluid, such as carbon dioxide. By mixing the syrup, the water and the gaseous fluid at the location where the drink is to be consumed and discharging the mixture in the proper amount to a drinking cup or glass, the expense of bottling may be removed and the expense of transportation may be greatly reduced since the tap water at the particular location may be used.

An object of my invention is to provide an improved mechanism for mixing and serving fluids automatically in predetermined quantities. Another object is to provide an improved mechanism for discharging liquids in predetermined quantities from separate sources to a common receptacle. Yet another object is to provide a mechanism for discharging syrup and water charged by a gaseous fluid in predetermined quantities to a common receptacle and, at the same time, delivering water from a source to a mixing chamber to which gaseous fluid is supplied under pressure.

A preferred form of my invention may include a piston having stepped portions that are reciprocable in cylinder bores having valve controlled intake and discharge passages communicating therewith. The space in one of the bores may be connected by its intake passage to a chamber containing syrup. The other bore may be connected at one side of the piston by its intake passage to a mixing chamber to which gaseous fluid, such as carbon dioxide, is supplied continuously under pressure, and to which water is supplied through the discharge passage communicating with the same bore at the other side of the piston. Water is supplied from a suitable source through the intake passage communicating with the end of the bore from which water is discharged to the mixing chamber. As the piston is moved through its discharge stroke, the syrup and charged water are desirably delivered through separate passage means to a nozzle where they are mixed and then discharged to a receptacle.

In the accompanying drawing there is shown for purposes of illustration one form which may invention may assume in practise.

In this drawing:

2

Fig. 1 is a vertical sectional view of my improved mechanism for mixing and serving fluids.

Fig. 2 is a plan view of Fig. 1.

Fig. 3 is a horizontal sectional view taken on the plane of the line 3—3 of Fig. 1.

Fig. 4 is a horizontal sectional view taken on the plane of the line 4—4 of Fig. 1.

Referring to the drawing it will be noted that there is shown a cylinder 1 having a bore 2 in which a portion 3 of a piston 4 is reciprocably received. A cylinder head 5 fits within the bore 2 and is provided with an enlarged portion 6 resting upon a shoulder 7 at the upper end of the bore. Extending into the cylinder head from its lower end is a bore 8 reciprocably receiving a reduced portion 9 of the piston 4. The piston portion 3 is shown herein as an annular member having a forced fit on the portion 9 so that they operate together as a single piston. Formed integrally with the piston portion 9 is a piston rod 10 extending from the lower side of the portion 3 through a lower cylinder head 12 which rests upon a split ring 14 fitting within an annular groove formed in the cylinder 1. Screws 15 extend through openings in a cap engaging the lower end of the cylinder and are threaded into openings in the lower cylinder head for holding it firmly in engagement with the ring 14. The diameter of the piston rod 10 is slightly greater than of the piston portion 9 for reasons that will shortly be described. For reciprocating the piston members there is provided a rod 17 pivotally connected to the piston rod 10 and carrying a sleeve portion 18 fitting over an eccentric cam 19 which is rotated by a power shaft 20. Any suitable power means, not shown, may be provided for rotating the shaft 20 through one revolution upon the insertion of a coin into a slot.

Arranged within the cylinder member 1 above the upper cylinder head is a block 22 held in engagement with a split ring 23 by screws 24 extending through openings in a cylinder cap 25 and threaded into openings in the block. Clamped between the block 22 and the cylinder head 5 is a baffle plate 26 which is curved, as shown in Fig. 3, so that its vertical edges are spaced apart a short distance to provide communication between the spaces 27 and 28 at opposite sides of the baffle. It will be noted that the baffle acts to hold the cylinder head 5 firmly in engagement with the shoulder 7.

Opening through the lower cylinder head 12 is a passage 30 for conducting water from a pipe connection 31 to the cylinder bore 2 at the lower 55 side of the piston portion 3. A ball valve 32 is

arranged in the passage 30 to prevent any water from being forced out of the bore 2 toward the pipe 31 when the piston 4 is moved downwardly in the bore. A spring 33 acts to move the ball valve toward its closed position, but the spring is sufficiently light so that pressure of the water supply will unseat the valve. A discharge passage 35 extends through the lower cylinder head from the bore 2 and is connected by a conduit 36 to a passage 37 extending through the block 22 into communication with the space 27. A nozzle 38 is connected in the discharge end of the passage 37 so that the water is introduced in a fine spray to the space 27. A ball valve 39 is arranged in the passage 37 to prevent the flow of fluid through the passage away from the space 27 and to permit flow in the opposite direction. A spring 40 urges the valve toward its closed position. Extending through the block 22 is another passage 42 for supplying a gas, such as carbon dioxide, from a supply connection 43 to the space 27. This gas is delivered to the space 27 at a pressure of approximately 100 pounds per square inch. As the water is sprayed into the space 27 it becomes thoroughly mixed with the gas and then passes between the ends of the baffle plate to the space 28. Extending through the cylinder head 5 is a passage 45 connecting the space 28 at the side of the baffle opposite the opening between its edges to the bore 2 at the upper side of the piston portion 3. A ball valve 46 permits the flow of mixed gas and water toward the bore 2 but prevents flow in the opposite direction.

As mentioned above the piston rod 10 is slightly larger in diameter than the piston portion 9. This means that the working space within the bore 2 beneath the piston portion 3 is slightly smaller than the working space above this piston portion. The difference between the volumes of these working spaces provides for the expansion of the water by its absorption of gas within the chamber spaces 27 and 28.

Opening into the bore 8 near its upper end is a passage 48 communicating with a conduit 49 which receives syrup from a suitable source. A spring pressed ball valve 50 opens to pass syrup toward the bore 8 and operates to prevent flow in the opposite direction. Another passage 52 opens through the cylinder head 5 into the bore 8 near its upper end and is connected to a conduit 53 which communicates with a passage 54 in a central body portion 55 of a nozzle 56. Opening through the cylinder head 5 into the upper end of the bore 2 is a passage 58 which is connected to a conduit 59 communicating with a passage 60 extending through a cap 61 threaded upon the body portion 55 of the nozzle. The passage 54 in the body portion 55 extends axially through the latter and opens into a space 62 within a cap 63 threaded upon the lower end of the body portion. Formed in the portion 55 around the passage 54 are several passages 65 for conducting fluid from the passage 60 to the space 62. Cooperating with the passage 60 is a spring pressed ball valve 66 which opens to pass fluid from the passage 60 to the passages 65 and closes to prevent flow in the opposite direction. Another spring pressed ball valve 67 cooperates with the passage 54 to pass fluid from this passage to the space 62 and to prevent flow in the opposite direction. The valve 67 is arranged at the discharge end of the passage 54 so that the syrup discharged from the latter is sprayed outwardly into the paths of the charged wa-

ter and is thoroughly mixed therewith. Opening through the cap 63 is a port 68 through which the mixed fluids may be discharged to a suitable container.

The operation of the mechanism described is as follows. The piston 4 normally assumes a position in which its portions 3 and 9 are located at the upper ends of the bores 2 and 8, respectively. The power mechanism driving the piston is so designed that it causes the piston to make one complete reciprocation when a coin is inserted. When the piston is in its upper position, the space in the bore 2 beneath the piston portion 3, the passage 35, the conduit 36 and the passage 37 up to the ball valve 39 are completely filled with water received from the conduit 31. As soon as the piston is moved downwardly, water charged by the carbon dioxide gas is taken from the space 28 through the passage 45 to the bore 2 at the upper side of the piston portion 3. The water at the lower side of the piston portion 3 is forced at the same time through the conduit 36, past the valve 39 and through the nozzle 38 to the chamber space 27. Since the water and gas are first mixed in the chamber 27 and must pass between the edges of the baffle and around the latter to reach the passage 45, it will be seen that a thorough mixing of the gas and water is obtained before it is discharged to the bore 2. Downward movement of the piston 4 also produces a flow of syrup to the bore 8 from the conduit 49. As the piston is moved upwardly to complete its reciprocation, syrup is forced from the bore 8 through the conduit 53 and the passage 54 to the space 62 in the lower cap of the nozzle 56. The charged water is forced from the bore 2 through the conduit 59, the passage 60 and the passages 65 to the space 62, and a new supply of water is taken from the conduit 31 into the bore 2 beneath the piston portion 3. The charged water and syrup are thoroughly mixed in the space 62 of the nozzle 56 and are discharged through the opening 68 to a suitable receptacle, not shown.

While there is shown in this application one form which my invention may assume in practice, it will be understood that the invention may be modified and embodied in various other forms without departing from its spirit or the scope of the appended claims.

What I claim as new and desire to secure by Letters Patent of the United States, is:

1. A mechanism of the character described comprising, in combination, means providing a plurality of bores of different diameters, piston portions reciprocable in said bores, means for reciprocating said piston portions in synchronism with each other, valve controlled intake and discharge passages opening into each of said bores adjacent one end, a chamber, means for supplying a gaseous fluid continuously to said chamber under pressure, means actuated by said piston reciprocating means for delivering a predetermined quantity of liquid to said chamber on each reciprocation of said piston portions, one of said intake passages communicating with said chamber for supplying a mixture of liquid and gaseous fluid to one of said bores, means for supplying a different fluid to another of said intake passages, a nozzle having separate passage means communicating with said discharge passages, a mixing chamber receiving fluid from said separate passage means, and passage means for discharging mixed fluids from said mixing chamber.

5

2. The mechanism of claim 1 including a baffle arranged in said first mentioned chamber to form a circuitous path through which the gaseous fluid and liquid must flow between the point at which they enter the chamber and are discharged therefrom to said one of said intake passages.

3. A mechanism of the character described comprising, in combination, means providing a pair of stepped bores opening into each other and closed at their outer ends, a piston having portions reciprocable in said bores, means including a piston rod connected to said piston for effecting reciprocation of the latter, valve controlled passage means for supplying a liquid to the larger one of said bores at one side of said piston, means providing a chamber, valve controlled passage means for conducting liquid from said larger bore to said chamber, means for supplying a gaseous fluid under pressure to said chamber, valve controlled passage means for supplying mixed gaseous fluid and liquid from said chamber to said larger bore at the other side of said piston, a valve controlled discharge passage communicating with said larger bore at said other side of said piston, valve controlled supply and discharge passages communicating with the smaller one of said bores, a nozzle having separate passage means communicating with the discharge passages from said bores and opening into a mixing chamber, and passage means for discharging mixed fluids from said mixing chamber.

4. A mechanism of the character described comprising, in combination, means providing a pair of stepped bores opening into each other and closed at their outer ends, a piston having portions reciprocable in said bores, means including a piston rod connected to said piston for effecting reciprocation of the latter, valve controlled passage means for supplying a liquid to the larger one of said bores at one side of said piston, means providing a chamber, a baffle arranged in said chamber for separating the latter into chamber spaces communicating with each other adjacent one side of the chamber, valve controlled passage means for conducting liquid from said larger bore to one of said chamber spaces, means for supplying a gaseous fluid under pressure to the one of said chamber spaces to which liquid is conducted, valve controlled passage means for supplying mixed gaseous fluid and liquid from the other of said chamber spaces adjacent the opposite side of said chamber to said larger bore at the other side of said piston, a valve controlled discharge passage communicating with said larger bore at said other side of said piston, valve controlled supply and discharge passages communicating with the smaller one of said bores, a nozzle having separate passage means communicating with the discharge passages of said bores and opening into a mixing chamber, and passage means for discharging mixed fluids from said mixing chamber.

6

5. The mechanism of claim 4 in which said piston rod has a diameter greater than that of the smaller portion of said piston and extends through the outer end of the larger one of said bores for connection to said piston, and the first mentioned one of said valve controlled passage means conducts liquid to the outer end of the larger one of said bores.

6. A mechanism of the character described comprising, in combination, a cylinder having a bore therein, cylinder heads supported within said bore at spaced points, a reduced bore formed in one of said cylinder heads and opening into said cylinder bore, a piston having portions reciprocably received in said bores, a piston rod extending through the other of said cylinder heads and connected to said piston for effecting reciprocation of the latter, a valve controlled intake passage extending through said other cylinder head into communication with said cylinder bore, means for supplying a liquid to said intake passage, a block supported within said cylinder at a point spaced from said one of said cylinder heads so as to form a chamber space therebetween, a valve controlled discharge passage extending through said other cylinder head into said cylinder bore and through said block into said chamber space, means for supplying a gaseous fluid continuously to said chamber space, a valve controlled passage extending from said chamber space through said one of said cylinder heads into said cylinder bore, a valve control passage for supplying fluid to one end of said reduced bore, a nozzle having separate valve control passages therein, passage means for connecting said separate passages in communication with said reduced bore and with said cylinder bore at its end adjacent said reduced bore, a mixing chamber in said nozzle receiving fluid from said separate passages, and passage means for discharging mixed fluids from said mixing chamber.

7. The mechanism of claim 6 in which the diameter of said piston rod is greater than that of said reduced bore.

8. The mechanism of claim 6 including a valve member cooperating with the end of one of said separate passages opening into said mixing chamber and operating when unseated to direct fluid as a spray into the path of the fluid discharged from the other of said separate passages.

CLARENCE JOHNSON.
